UNITED STATES PATENT OFFICE.

ERICH J. PATELSKI, OF CHICAGO, ILLINOIS.

ELECTRIC-RAILWAY SYSTEM.

1,274,076.

Specification of Letters Patent. Patented July 30, 1918.

Application filed March 8, 1915, Serial No. 12,783. Renewed August 23, 1916. Serial No. 116,560.

To all whom it may concern:

Be it known that I, ERICH J. PATELSKI, a citizen of the United States of America, and resident of Chicago, Cook county, Illinois, (res. 3971 Langley Ave., bus. add. 167 W. Washington St.,) have invented a certain new and useful Improvement in Electric-Railway Systems, of which the following is a specification.

10 My invention relates to electric railway systems of that kind in which the current is not conveyed to the moving cars through the medium of a continuous conductor, such as a third rail or trolley wire, but simply through the medium of current feeding contacts disposed along the track, and in which the cars are provided with shoes or long conductors arranged to slide on said contacts, the distance between the latter being such 15 that the cars are always in touch with at least one of said contacts. In this way, as will be readily understood, the dangers which usually attend the use of third rails and trolley wires are entirely avoided, and 20 25 other objections as well.

My present invention is, therefore, in the nature of an improvement on the electric railway system shown and described and claimed broadly in my co-pending application No. 12782, filed of even date herewith.

The object of my invention, as herein disclosed, is to provide a novel and satisfactory construction and arrangement in which the contacts which are arranged at intervals along the track are disposed in fixed position, are not movable, and are connected at all times with the main current conductor which leads to the power station.

Another object is to provide a more practical arrangement than heretofore, involving a construction and arrangement of such character that the current feeding contacts are arranged outside of the rails, the shoes or conductors which engage these contacts 40 45 50 being arranged at the side of the cars, and each shoe or conductor being yieldingly presented to the contacts, whereby the vibration or lurching of the cars does not interfere with the supply of current to the motors thereof, notwithstanding the fixed character of the current feeding contacts along the track.

It is also an object to provide certain details and features of construction and combinations tending to increase the general

efficiency and desirability of an electric railway system of this particular character.

To the foregoing and other useful ends, my invention consists in matters hereinafter set forth and claimed.

60

In the accompanying drawings—

Figure 1 is a side elevation of a section of track and of the trucks of an electric locomotive of a railway system embodying the principles of my invention.

65

Fig. 2 is a plan of one-half of the structure shown in Fig. 1, showing the car trucks traveling on a straight length of track.

Fig. 3 is a view similar to Fig. 2, but showing the trucks traveling on a curved section of track.

Fig. 4 is an enlarged section on line 4—4 in Fig. 1.

Fig. 5 is an enlarged side elevation of one of the brackets and contacts which are disposed along the track, showing the upper portion thereof in section.

Fig. 6 is a detail section on line 6—6 in Fig. 5.

Fig. 7 is a diagram of the circuit arrangement employed in Fig. 4.

Fig. 8 is a view similar to Fig. 4, showing current feeding contacts at both sides of the track, and showing the car provided with shoes or conductors for engaging said contacts at both sides thereof.

Fig. 9 is a plan of the bracket shown in Figs. 5 and 6.

Fig. 10 is a diagram of the circuit arrangement employed in Fig. 8.

As thus illustrated, the trucks A travel on the rails B in the usual and well known manner, and are provided with motors C, of any suitable character, for the propulsion thereof. As shown in Fig. 4, brackets D are arranged at intervals along the track, at one side thereof and are each provided with an insulated contact d, these contacts being suitably connected with the current main by insulating wires d¹ leading upwardly thereto. A housing E is secured to the side of the trucks, said housing being reticulated and having joints at e which enable it to bend when the trucks are passing around a curve. (See Fig. 3.) This housing is open at its outer side to receive the brackets D and is provided internally with a shoe or flat conductor e¹, the latter being insulated on its under surface and supported by springs e², whereby these shoes or conductors are adapt- 95 100 105 110

ed to move up and down and are yieldingly presented to the under sides of the contacts d while the cars are traveling along the track. During this time the springs resist any inclination of the train to rise. It will be understood that the shoes or conductors e^1 are suitably connected with the motors C, and that the latter are electrically connected with the car wheels, whereby the rails are used as a part of the circuit. (See Fig. 7.) The distance between the contacts d is such that the shoes or conductors e^1 of the electric locomotive are always in engagement with at least one of said contacts, whereby the circuit is not broken by the forward movement of the cars. The springs e^2 serve to keep the shoes or conductors e^1 firmly in engagement with the contacts d , notwithstanding the vibration and lurching of the cars, and thus a good circuit connection is provided at all times. As shown, the strip e^1 is of a thickness to flex or bend as it passes under the contact on the member D, as will be readily understood. It will also be observed that this strip must be constructed in any suitable manner to partake of the flexing action of the housing at the joints thereof.

In Figs. 8 to 10 inclusive, the construction is substantially the same as that previously described, except that in this case the brackets D and their contacts d are employed at both sides of the track. In this way the wheels of the cars and also the rails of the track are not included in the current circuits. In Fig. 4 the shoes or conductors e^1 are employed at both sides of the cars, so that the latter can travel in both directions on the track, without traveling backward, which is essential and desirable in the case of the power car or electric locomotive. In Fig. 8, however, there is a full equipment at each side of the electric locomotive or car, and the latter can travel in opposite directions without turning around, assuming that suitable switches and circuit controlling devices are employed on the locomotive or car for reversing the direction of travel thereof. In Fig. 8 the circuit arrangement is of the character shown in Fig. 10, the current being supplied over cables or mains arranged at opposite sides of the track.

Thus fixed contacts are employed along the track, thereby obviating the necessity of using switches for connecting the contacts with the current mains, and simplifying the construction materially.

Dust and sand cannot collect on the contacts of the posts D, as they are inverted, even though they are out of action for some time; and the wide overhang of the housing E protects the strip e^1 against the weather. The vibration of the train will tend to prevent sand or dust from settling on the strip e^1 , and this flexible strip is kept

clean by the practically constant rubbing action.

What I claim as my invention is:—

1. An electric railway system comprising a housing carried by the rolling stock and constructed of reticulated sections to permit lateral flexing thereof when the trucks travel around curves in the track, said housing being open along one side thereof, members disposed along the track to enter the front end of said housing and leave at the rear end thereof, a contact strip extending longitudinally within said housing, insulated contacts fixed on said members, the arrangement being such that the upper surface of said contact strip engages the under sides of said contacts by upward pressure, springs disposed in a plane below said strip to yield under said pressure, said members being such a distance apart that said strip is always in engagement with at least one of said contacts, and means to connect said contacts with a source of current, said members being held in fixed position, and said springs being covered by said housing. 90

2. An electric railway system comprising a housing carried by the rolling stock and constructed of reticulated sections to permit lateral flexing thereof when the trucks travel around curves in the track, said housing being open along one side thereof, members disposed along the track to enter the front end of said housing and leave at the rear end thereof, a contact strip extending longitudinally within said housing, insulated contacts fixed on said members, the arrangement being such that the upper surface of said contact strip engages the under sides of said contacts by upward pressure, springs disposed in a plane below said strip to yield under said pressure, said members being such a distance apart that said strip is always in engagement with at least one of said contacts, and means to connect said contacts with a source of current, said members being held in fixed position, and said springs being covered by said housing. 95

3. An electric railway system comprising a housing carried by the rolling stock and constructed of reticulated sections to permit lateral flexing thereof when the trucks travel around curves in the track, said housing being open along one side thereof, members disposed along the track to enter the front end of said housing and leave at the rear end thereof, a contact strip extending longitudinally within said housing, insulated contacts fixed on said members, the arrangement being such that the upper surface of said contact strip engages the under sides of said contacts by upward pressure, springs disposed in a plane below said strip to yield under said pressure, said members being 110

such a distance apart that said strip is always in engagement with at least one of said contacts, and means to connect said contacts with a source of current, said members and housing being disposed at one side of the track and trucks, outside of the rails and wheels, and said housing being open at its outer side and jointed at its inner side.

4. An electric railway system comprising 10 a housing carried by the rolling stock and constructed of reticulated sections to permit lateral flexing thereof when the trucks travel around curves in the track, said housing being open along one side thereof, members 15 disposed along the track to enter the front end of said housing and leave at the rear end thereof, a contact strip extending longitudinally within said housing, insulated contacts fixed on said members, the arrangement 20 being such that the upper surface of said contact strip engages the under sides of said contacts by upward pressure, springs disposed in a plane below said strip to yield under said pressure, said members being 25 such a distance apart that said strip is always in engagement with at least one of said contacts, and means to connect said contacts with a source of current, said springs being a yielding support for said strip in the 30 housing.

5. An electric railway system comprising a housing carried by the rolling stock and constructed of reticulated sections to permit lateral flexing thereof when the trucks travel around curves in the track, said housing being open along one side thereof, members 35 disposed along the track to enter the front end of said housing and leave at the rear end thereof, a contact strip extending longitudinally within said housing, insulated contacts fixed on said members, the arrangement 40 being such that the upper surface of said contact strip engages the under sides of said contacts by upward pressure, springs disposed in a plane below said strip to yield 45 under said pressure, said members being such a distance apart that said strip is always in engagement with at least one of said contacts, and means to connect said contacts with a source of current, said strip being 50 flexible, and said springs being disposed at intervals below said strip on the bottom of said housing.

Signed by me at Chicago, Illinois, this 5th day of March, 1915.

ERICH J. PATELSKI.
